Nelson M. Howard

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

HEEL-ATTACHING DEVICE.

Application filed February 19, 1919, Serial No. 277,932. Renewed November 29, 1922.

To all whom it may concern:

Be it known that I, JOSEPH H. POPE, a citizen of the United States, residing at Hamilton, in the county of Essex and State of Massachusetts, have invented certain Improvements in Heel-Attaching Devices, of which the following description, in connection with the accompanying drawings, is a specification, like reference characters on the drawings indicating like parts in the several figures.

This invention relates to heel attaching devices and, more particularly, to a device for use in attaching wooden or other ogee heels which must be secured by nails or screws driven from the inside of the shoe.

In a considerable number of factory made shoes, and in substantially all repair work, heels of the type mentioned are attached manually, the heel usually being located by hand upon the shoe sole according to the judgement of the workman and attached by nails or screws driven by hand inside of the heel portion of the shoe. In this method of heel attaching, the heels are often inaccurately located and frequently slip while being attached, with resulting detriment to the appearance of the shoe.

The object of the present invention is to overcome the difficulties above outlined and to provide an appliance for facilitating the attachment of heels to shoes and insuring accurate and satisfactory results with a minimum of skill on the part of the operator. To this end an important feature of the invention resides in novel mechanism for supporting and locating a detached heel with its seat face exposed to permit a shoe to be adjusted upon it, and then clamping and holding the shoe and heel securely together while the fastenings are being driven. In a preferred embodiment of the invention the heel is grasped and held in a device or holder in a convenient position to permit the shoe to be placed upon it and a swinging clamping member is arranged to enter the shoe while thus positioned and clamp it firmly to the heel. The clamping member may include means for determining the location of the fastenings, and a further feature of the invention consists in so organizing the clamping member or the positioning means that it may be collapsed with its fastening-locating means to permit its easy

introduction into the shoe and then expanded to engage the inside of the counter portion of the shoe to insure the proper location of the heel seat in accurate register with the heel.

These and other features and advantages of the invention will be clearly understood from reading the following detailed description of one practical embodiment thereof in connection with the accompanying drawings, in which—

Figure 1 is a view in front elevation showing the mechanism with a shoe and heel in position for inserting the heel attaching fasteners;

Fig. 2 is an end elevation of a portion of the device;

Fig. 3 is a perspective view of the clamping member and template;

Fig. 4 shows a detail of the heel supporting and locating device; and

Fig. 5 is a fragmentary, sectional view illustrating the manner of preparing the work and driving a fastener.

My improved heel attaching device is especially useful in repair shops and, with so that fact in view, it is preferably constructed in a conveniently portable form and arranged to be secured quickly and easily to any work bench or table. Referring now to Fig. 1, the edge of a bench or table is shown at 8. The heel attaching device is provided with a flat base 10 arranged to rest upon the table 8 and provided with a downwardly extending arm 12, through which is threaded a clamping screw 14, by which the device may be easily and quickly secured to the table. A pair of uprights 16 rising from the rear portion of the base member 10 provide bearings for a longitudinal rod 18, upon which swings a cradle 20, the base plate 22 of which carries the operating mechanism.

Guide slots 24 are formed in the cradle 20 to receive co-operating portions of an adjustable block 26. A thumb screw 28, held from longitudinal movement in a stationary bearing 30, is threaded into the block 26, as shown in dotted lines in Fig. 1 and serves to adjust the block lengthwise of the guiding grooves 24.

A pair of crossed arms 32, 34 is mounted upon the block 26 by a pivot 36. The rearward extensions of the arms 32, 34 are con-

nected by a right and left screw 38 provided with a thumb nut 40. By virtue of this construction, the arms or jaws 32, 34 may be easily adjusted toward or from each other to fit the particular heel 42 to be attached. The heel is shown in cross section in Fig. 4 in its relation to the jaws of the supporting device which serves to sustain the heel and position it for the application 10 of the shoe. The cradle is extended to provide a plate 44 for sustaining the forepart of the shoe and locating it with relation to the heel so that the heel will tread properly. To this extension a swinging arm 46 is pivoted, the pivot pin being provided with a handle 48 for moving the arm into and out of operative position. In Fig. 1 the arm is shown in full lines in operative position and indicated in dotted lines in inoperative position. 15 A lug 50 upon the arm co-operates with an abutment 52 to limit the swinging movement of the arm. A spring actuated dog 54 is pivoted at 56 to the arm 46 and co-operates with a stationary ratchet segment 20 58 to lock the arm in clamping position. A handle 60, integral with the dog, permits it to be unlocked to release the clamping arm when desired.

The actual clamping member which directly engages the shoe is best illustrated in Fig. 3. A tube 62, mounted in the rear end of a plate 64, secured by bolts 66 to the end of the arm 46, serves as a pivot for two counter gages 68, 70, which are mounted to 25 swing freely about the axis of the tube. A spindle 72, provided with a handle 74, is rotatably mounted in a bearing 76 formed in the arm 46, being held from longitudinal movement therein by a collar 78 pinned to 30 the spindle above the bearing and a transverse bar 80 secured to the lower end of the spindle below the bearing. Pins 82, inserted in the ends of the bar 80 and extending downwardly therefrom, are engaged by 35 extensions 84, 86 of the counter gages 68, 70, serving to limit the outward movement of the gages about the pivot tube 62 under the influence of the compression spring 88. The pins 82 are spaced apart to permit the 40 counter gages to expand sufficiently to engage the largest shoe to be operated upon. When it is desired to introduce the clamping member into a shoe, the handle 74 is turned, causing the counter gages to be 45 brought together to an extent sufficient to permit the clamp to be inserted in the shoe, whereupon the handle is released and the spring 88 causes the counter gages to expand until they engage the inside of the counter 50 portion of the shoe, to locate the shoe properly with relation to the heel.

A series of tubes 90 mounted in the counter gages, together with the tube 62, serve as guides to locate the fastenings and as supports for the fastening inserting device.

Referring now to Fig. 5, 92 and 94 indicate respectively two positions of a special tool which may be conveniently utilized for drilling holes in the work and inserting screw fastenings. As shown, the tool is double ended, having a drill and countersink 70 96 at one end and a screw driver point 98 at the other end. This tool may conveniently be held in the chuck of an ordinary hand drill, as indicated in dotted lines at 100. The end 96 is used to drill and countersink the work, as shown at 102, after which the screw driver end of the tool is used to insert a screw in the hole thus prepared, as shown at 104.

The operation of the device will be apparent from the foregoing description but may be outlined and summarized as follows: Assuming the clamping arm 46 to be in the position indicated by dotted lines in Fig. 1, the jaws 32, 34 are adjusted to the particular heel to be attached and the heel is located in them in the position shown in the said figure. The shoe is now placed upon the heel in the position shown, with its forepart resting upon the supporting plate 44 and the arm 46 is swung into clamping position, the clamping member comprising the counter gages 68, 70 being collapsed to permit the said member to enter the shoe readily and then released to cause it to fill the rear portion of the shoe and position the latter transversely with respect to the heel. The heel holder may be adjusted by means of the screw 28 to position the heel longitudinally in exact relation to the shoe and the clamping arm forced down to hold the shoe firmly upon the heel, where it will be automatically locked by the dog 54.

The entire cradle, with the work clamped in position, may, if desired, now be swung about the rod 18 to permit the work to be thoroughly examined to ascertain if the desired relative location of the heel and shoe have been secured. If the result is satisfactory, the cradle is swung back to the position shown in Fig. 1 and the holes are drilled and countersunk, using the tubes 62 and 90 to guide the tool. The tool is now reversed and, a screw having been dropped 105 point first into each tube, the screw driver end of the tool is used to drive the screws to secure the heel and shoe together. The tubes likewise serve in this operation to guide the screw driver and make it possible 110 to perform the operation of driving the screws very rapidly and accurately without the exercise of any special care or skill.

If it be desired to use nails for fastenings they may be inserted through the tubes and 115 driven with an ordinary punch or driver, holes for their reception having been previously pricked with an awl, if desired, although this may not be necessary.

The locking dog 54 is now released and the 120

clamping arm 46 swung outwardly, whereupon the shoe may be removed and the operation repeated upon another shoe.

Having described my invention, what I claim as new and desire to secure by Letters Patent of the United States is:—

1. In a heel attaching device, the combination of means for supporting and holding a detached heel in a predetermined position with its seat face unobstructed to permit a shoe to be placed upon it manually, a support for the shoe adjacent to the heel-holding means, and means movable into engagement with the shoe for clamping it upon the heel.
2. In a heel attaching device, the combination of a holder constructed and arranged to support and position a detached heel with its seat face exposed to permit a shoe to be adjusted upon it, and means movable into engagement with the shoe for maintaining proper location of the shoe with respect to the heel and clamping the shoe upon the heel in adjusted position, said engaging means being arranged to permit the attaching means to be driven from the interior of the shoe into the heel.
3. In a heel attaching device, the combination of a holder constructed and arranged to grasp and hold a detached heel with its seat face upward to permit a shoe to be placed upon it, and a clamping member arranged to swing into the positioned shoe and clamp it upon the heel.
4. In the device of the class described, the combination of a device arranged to position a heel and hold it fixed against movement independently of a shoe, and a clamping member constructed and arranged by a single swinging movement to enter a shoe previously placed upon the heel and clamp the shoe and heel together.
5. In a device of the class described, the combination of means for holding a detached heel with its seat face upward to permit a shoe to be adjusted upon it, and a clamping member movable into the shoe and provided with fastening and driver guiding passages, said passages being arranged to permit free and unobstructed introduction of the fastening means and the application of a hand-tool to effect the attachment.
6. In a device of the class described, the combination of means arranged to grasp and hold a detached heel with its seat face exposed to permit a shoe to be adjusted upon it, a swinging clamping member constructed and arranged to enter the shoe and clamp it upon the heel, and means for automatically locking said member in clamping position.
7. In a device of the class described, the combination, with shoe supporting means, of a collapsible clamping member provided with fastening-receiving means and con-

structed and arranged to enter a shoe carried by the support, and means for expanding said member within the shoe.

8. In a device of the class described, the combination, with work supporting means, of a collapsible clamping member having fastening-receiving passages and constructed and arranged to enter a shoe, and means for expanding said member within the shoe to engage the inside thereof at the counter portion only.

9. In a device of the class described, the combination, with work supporting means, of a clamping member constructed and arranged to enter and approximately fill the counter portion only of a shoe, a support for the clamping member mounted to swing over the forepart of the supported shoe to bring said clamping member directly into the counter portion, and means for expanding said member transversely within the shoe to cause it to engage the inside of the counter portion thereof.

10. The combination, with a collapsible clamping member constructed and arranged to enter the counter portion of a shoe, of means tending normally to keep said member expanded, means for collapsing said member to permit it to enter the shoe easily, said means being arranged for manipulation by the operator during the entering movement, and external work supporting means for resisting the clamping pressure of said member.

11. In a device of the class described, the combination of means for positioning and holding a heel in a predetermined transverse position with its seat face exposed to permit a shoe to be adjusted upon it, a collapsible clamping member movable in a predetermined path to enter the rear portion of the shoe and clamp it upon the heel, and means for expanding said member transversely within the shoe to engage the sides thereof and maintain transverse register of the shoe with the heel.

12. A collapsible clamping member, constructed and arranged to enter a shoe, comprising pivoted counter gages 68, 70, means for forcing them apart, a rotatable spindle 72, and spaced members 82 movable with the spindle and engaging the outside faces of the counter gages.

13. In a heel-attaching device, the combination with a work-support, of a collapsible positioning means for heel-attaching instrumentalities movable into and out of a supported shoe.

14. In a heel-attaching device, the combination with a work-support, of a collapsible combined shoe clamp and positioning means for heel-attaching instrumentalities movable into a shoe situated upon the support to clamp it thereon.

15. In a device of the class described, the

combination of a base member, a cradle hinged thereto and normally resting solidly thereon but swinging about its hinge to invert the work, a heel holder upon the cradle and means upon the cradle for clamping a shoe upon a heel in the holder.

16. A clamping device comprising, in combination, a means to hold a Louis heel upright and to support it against downward pressure by engaging its lateral surface, a support for the forepart of a shoe with its heel seat on a heel held by the first support, and a swinging member to clamp the shoe against the heel.

17. A clamping device comprising, in combination, a stationary support to hold a Louis heel upright by engaging the upper portion of its lateral surface, a second stationary support for the forepart of a shoe with its heel seat on a heel held by the first support, and a member swinging longitudinally of the shoe to clamp the shoe against the heel.

18. A clamping device comprising, in combination, a rigid support to hold a Louis heel in a predetermined upright position by engaging its lateral surface, and a member swinging longitudinally of a shoe to clamp the heel seat of the shoe against the seat surface of the heel.

19. Heel-attaching apparatus comprising, in combination, a support to hold a Louis heel upright by engaging its lateral surface, a device permanently connected with said support, said device having a substantially vertical perforation and arranged to be operatively positioned in a shoe with the heel seat of the shoe registered on the heel, and with the perforation unobstructed, and means for applying pressure to said device to hold the device and shoe and heel clamped together, said device and means being constructed and arranged to permit a drill to be directed manually through said perforation to drill a hole through the heel seat of the shoe into the heel and a fastening to be driven through the perforation into the heel so formed.

20. A heel-attaching device to be inserted in a shoe, having an unobstructed cylindrical opening of substantial length therethrough

constructed and arranged to guide a drill to form a hole through the heel seat of the shoe into a heel and to guide a screw driven into the hole so formed, in combination with a rigid support to engage by its lateral surface a Louis heel seated on the shoe and firmly to support the heel while said screw is being driven therein.

21. A heel-attaching device to be inserted in a shoe comprising, in combination, a pair of members carrying fastener guides, a spring urging said members apart against the sides of the counter portion of a shoe, and means to contract said members against the resistance of the spring to facilitate inserting the device into a shoe.

22. A heel attaching device comprising, in combination, a head having a set of nail tubes mounted to be expanded outwardly toward the inside of the counter portion of a shoe and to be contracted, means urging the tubes outwardly into different positions determined differently by different shoes independently of the operator, and means to contract the tubes into a smaller compass to facilitate relative movement of the head and each shoe.

23. A heel holder comprising, in combination, an adjustable block, and an adjustable pair of jaws carried thereby to engage opposite sides of a Louis heel to hold the heel upright with its seat surface unobstructed.

24. A holder as defined by claim 23, in combination with a pivoted presser swinging longitudinally of a shoe to press the shoe against a heel held by the jaws.

25. Apparatus for clamping a Louis heel to the heel-seat of a shoe comprising, in combination, a device to support a shoe, a device to engage the side surface of the Louis heel in a manner rigidly to support it against pressure perpendicular to the seat surface, means to move one of said devices toward the other to clamp the heel and shoe together with pressure substantially perpendicular to the heel seat, and a one-way retaining member to hold the devices in clamping position.

In testimony whereof I have signed my name to this specification.

JOSEPH H. POPE.
